UNITED STATES PATENT OFFICE

CHARLES J. McCABE, OF BROOKLYN, AND IRVING SCHOENHOLZ, OF CEDARHURST, NEW YORK, ASSIGNEES TO McCABE AND SCHOENHOLZ, INC., OF NEW YORK, N. Y., A CORPORATION OF NEW YORK

DESIGN FOR A POCKETBOOK LATCH

Application filed June 28, 1929. Serial No. 31,867. Term of patent 7 years.

To all whom it may concern:

Be it known that we, CHARLES J. McCABE, a citizen of the United States, residing in Brooklyn, county of Kings, and State of New York, and IRVING SCHOENHOLZ, a citizen of the United States, residing in Cedarhurst, Long Island, county of Nassau, and State of New York, have invented a new, original, and ornamental Design for a Pocketbook Latch, of which the following is a specification, reference being had to the accompanying drawing, forming part thereof.

We claim as our invention:

The ornamental design for a pocketbook latch substantially as shown.

C. J. McCABE.
IRVING SCHOENHOLZ.
